US00D595707S

(12) **United States Design Patent**
Miles et al.

(10) **Patent No.:** US D595,707 S
(45) **Date of Patent:** ** Jul. 7, 2009

(54) **HANDSET**(75) Inventors: **Luke Miles**, London (GB); **Rachael Sleight**, London (GB)(73) Assignee: **Nokia Corporation**, Espoo (FI)(**) Term: **14 Years**(21) Appl. No.: **29/299,240**(22) Filed: **Dec. 20, 2007**(30) **Foreign Application Priority Data**

Jun. 20, 2007 (FI) M20070121

(57) **CLAIM**

The ornamental design for a handset, as shown and described.

DESCRIPTION

FIG. 1 is a front view of a handset showing our new design; and,

FIG. 2 is a front perspective view thereof.

The broken lines showing environmental structures is for illustrative purposes only and forms no part of the claimed design.
